UNITED STATES PATENT OFFICE.

WILLIAM R. MOORE, OF EAST ORANGE, NEW JERSEY.

DOOR BUZZER OR BELL.

950,185.

Specification of Letters Patent. Patented Feb. 22, 1910.

Application filed December 23, 1908. Serial No. 469,029.

To all whom it may concern:

Be it known that I, WILLIAM R. MOORE, a citizen of the United States, residing at East Orange, in the county of Essex and State of New Jersey, have invented certain new and useful Improvements in Door Buzzers or Bells, of which the following is a specification.

My invention relates to that class of bells commonly known as buzzers and the invention has for its object to provide means for communicating with others by sound from those occupying rooms in hotels, &c.

With these and other objects in view the invention consists in the novel construction and combination of parts as will be herein-after more in detail described, and the asserted novelty distinctly claimed.

I have fully and clearly illustrated my invention in the accompanying drawings in which;

Figure 1 represents a sectional elevation of my device as applied to a portion of a door, and Fig. 2 is a plan view thereof. Fig. 3 is a detached view of a slotted loop which holds in operative engagement the spiral or worm.

Similar letters of reference indicate corresponding parts in the several figures.

Referring to the drawings; A designates a portion of a door having an opening *a* formed therethrough. B designates a flanged circular base plate secured to the inner side of said door by means of screws *b*, *b*, this plate being provided with an opening C formed in alignment with the opening *a* in the portion of the door.

D designates a push-button rod having a flanged push-button *d* secured upon its outer end, the flanged portion *d'* of which when in its normal position bears against the inner flange *e* of a thimble F let within the opening *a* in the door portion A, the outer flange of the thimble bearing against the door portion and encircling the push-button *d*. The inner end of this push-button rod D is passed through the opening *a* in the door portion and also through the opening C in the circular flanged plate B and having a head *c* thereon for holding it in engagement with a loop for a purpose which will be hereinafter explained.

F' designates a horizontally disposed plate provided with flanges *F'* and *F''* at each end, said flanges extending in opposite

directions, the inner one of said flanges being secured to the base-plate.

G designates a short rod having its forward end secured to the flanged circular base plate B and its rear end secured to the rear angular portion *F''* of the horizontally disposed plate F'.

H designates a strip of metal having its end turned back upon itself and forming a loop *h*, said loop having perforations *h'* and *h''* therein and in alignment with each other, and through which the short rod G is passed and upon which the loop *h* is operatively engaged traversing the rod G back and forth.

I designates a coiled spring, one end of which engages the loop *h*, its opposite end bearing against the outer flange of the plate F'. The end of the bent back portion of strip H is bifurcated to receive therein a spiral or worm J which is in operative engagement therewith, an opening *j* being formed in the rear angular portion of the horizontal angular plate F' through which the spiral or worm is passed.

K designates an angular arm of metal having an opening *k* formed centrally therethrough midway its length, the ends of said arm terminating in U-shaped loops within which are journaled rollers or wheels L, the rear end of the spiral or worm having a nut or washer *l* thereon, thus securing by means of a pin *l'* the angular arm K upon the rear end of said spiral or worm.

M designates a bell provided with a multiple number of indentations in circular series upon the outer surface and upon the inner surface protuberances, and when the bell is secured to the circular flanged plate and in its closed or normal position the wheels through the medium of the mechanism contact with these protuberances and produce a buzzing sound similar to those bells electrically operated. The bell is detachably secured to the circular base plate by lugs or any suitable fastening means.

My device is always ready for use, never in the way, occupying but little space, does not get out of order, and dispenses with the usual hammers, the wheels producing an electrical imitation giving eighty-four strokes upon the bell at each push of the button.

The operation of my device will be obvious when taken in connection with the ac-

companying drawings, and further description hereof is deemed unnecessary.

What I claim as new and desire to secure by Letters Patent is;

- 5 1. The combination with the door, a circular flanged base-plate secured to the door, a push-rod passed through openings formed in said door and base-plate, of a horizontal plate provided with a flange at each end thereof, the flanges extending in opposite directions the inner of said flanges being secured to the base-plate, a short rod having one end secured to the base-plate and the opposite end to the outer flange, a metal strip bent back upon itself and forming a loop member provided with alined openings through which the push-rod passes, the said push rod being secured to said loop member, a bifurcation formed in each end of said loop member, a spring having one end secured to the loop member and the opposite end to the inner face of said outer flange, a spiral rod rotatably secured in the base-plate and taking in the bifurcations formed in the loop member, and its rear end passed through an opening formed in said outer flange, an angular arm having an opening formed midway its length through which the rear end of the spiral rod is passed and operatively secured to the outer flange of the horizontal plate, the outer ends of said angular arm terminating in forwardly projecting U-shaped loops, wheels journaled in said loops, and a bell with indentations and
- 10
- 15

- 25
- 30

protuberances formed upon its inner and 35 outer surfaces in circular series over the latter of which the wheels travel.

2. The combination with the door, a flanged circular base-plate secured to the door, a push-button rod passed through 40 openings formed in said door and base-plate, a horizontal plate provided with a flange at each end thereof, the flanges extending in opposite directions, the inner of said flanges being secured to the base-plate, 45 a short rod having one end secured to the base-plate and the opposite end to the outer flange, of a metal strip bent back upon itself and forming a loop member provided with alined openings through which the push-rod 50 passes, the said push-rod being secured to said loop member, a bifurcation formed in each end of said loop member, a spring having one end secured to the loop member and the opposite end to the inner face of said 55 outer flange, a spiral rod rotatably secured in the base-plate and taking in the bifurcations formed in the loop member, and its rear end passed through an opening formed in said outer flange, striking mechanism mounted upon the end of said spiral rod, and a bell mounted upon said base-plate.

In testimony whereof I affix my signature in presence of two witnesses.

WILLIAM R. MOORE.
